UNITED STATES PATENT OFFICE

JOHANN PLESCH, OF BERLIN, GERMANY

BLOOD PRESSURE TOURNIQUET

Application filed May 27, 1931, Serial No. 540,423, and in Germany June 3, 1930.

Blood pressure tourniquets may be divided into two groups. In one kind a strap of woven fabric or rubber, with reinforcement, has at one part thereof an inflatable air cushion, so that a yielding pressure is exerted only on one part of the arm embraced by the strap. In the other kind the strap forms an air cushion throughout its length, and makes more than a complete turn round the arm, according to the thickness of the latter. There may be two or more complete turns in the case of a child. This leads to inaccurate hydrodynamic results when making the measurement. Put shortly, the air cushion is too small in one case and too large in the other.

The object of my invention is to remove this defect, and to this end I use a strap which is inflatable throughout its length but only becomes effective, as an air cushion, to the extent of whatever portion thereof is required to make one turn round the arm. For this purpose the strap has attached to one end thereof a fastener through which the other end is drawn to tighten the strap, and the fastener, when put into operation, applies a grip across the strap, so that the loose portion of the air cushion, drawn through the fastener, is shut off from the remaining part.

Another advantage of the improved tourniquet is that the fastener can operate at any desired angle across the part which it grips, so that the strap can accommodate itself closely to the arm, more so than is the case with the usual fasteners.

After inflation the whole circumference of the arm is effective for enabling pulsation to be observed.

To ensure that the air pressure compresses only the arm, without bulging the outside wall of the cushion and giving a wrong impression in regard to the pulse action, the outside wall is reinforced by a non-extensible lining, e. g. wire fabric, thin sheet metal or the like, which does not interfere with the transverse shutting off of part of the air cushion, but even assists it. The inflated strap consequently only bulges inwards, instead of assuming a bi-convex shape, as was hitherto the case.

A blood pressure tourniquet according to

the invention is shown in the accompanying drawings, Fig. 1 being a cross-section thereof, Figs. 2 and 5 being elevations, and Figs. 3 and 4 being cross-sections showing the fastener in two positions.

The cover *a* is placed round a strip *b* of metal, so that it cannot be stretched longitudinally, and also cannot be stretched transversely if the strip *b* is of woven wire or sheet metal. There is an inside layer *c* of rubber, leaving a cavity *d* communicating with a tube *e*, for inflation by means of air or other gas, or for introducing a liquid, e. g. glycerine.

The strap has at one end a loop *f*, whereby it is engaged with a part *g* of the fastening device. The fastening device consists in part of a tube *h* with portions of its wall cut away to afford a passage for the free end of the strap. The part *g* is a portion of the tube wall, between the two gaps. At the ends of the tube there are caps *m*, *n*, and within the tube is a rod *i* of circular cross-section, having at its ends eccentric pivots whereby it is mounted in the said caps. The free end of the strap passes through the tube between the tube wall and the eccentrically mounted rod *i*, and by turning the rod the strap can be squeezed against the tube wall, and thus fastened. The rod *i* is rotated by means of a handle *k* at one of its ends, and it has upon it a rotatable sheath *r* enabling the strap to slide over it easily when not squeezed. There is a thick bead *s* at the free end of the strap, preventing its complete withdrawal from the tube *h*.

Fig. 4 shows the rod *i* in a position allowing the free end of the strap to slide freely thereon, when adjusting it on the patient's arm. After adjustment the strap is tightened as required, and the handle *k* is then rotated to the position shown in Fig. 3, causing the rod *i* to squeeze the free end of the strap, and hold it fast. If the patient's arm is approximately cylindrical at the part to which the strap is applied the strap assumes a corresponding shape, as shown in Fig. 2. If the arm is tapered the strap assumes the conical shape shown in Fig. 5.

When the strap is worn out, or is to be

changed for one of a different size, the fastener need not be discarded. The cap *n* can be removed, after unscrewing a screw *u* by means of which it is held, and the loop *f* can 5 then be slipped off the part *g*, a fresh strap being substituted, whereupon the cap *n* is replaced.

What is claimed is:

1. A blood-pressure tourniquet, forming 10 an air cushion throughout its length, characterized in that the strap has at one end a fastener, through which the other end passes and by which said other end can be gripped along a transverse portion thereof, so that 15 the air cushion is closed by the grip, and the portion of the strap drawn through the fastener is not inflated, said portion drawn through the fastener having an enlargement (s) preventing complete withdrawal there- 20 of from the fastener.
2. A blood pressure tourniquet according to claim 1, characterized in that its outer layer is so reinforced by a non-extensible but 25 flexible inlay (b) that when under pressure the strap can only expand inwards.
3. A blood pressure tourniquet according to claim 1, characterized in that the fastener comprises a tube cut away so as to leave only 30 two longitudinal parts (*h*, *g*), with two caps (*m*, *n*) on said tube, and a rod (*i*) mounted in said tube for eccentric rotation, the part (*h*) of the tube forming a seat against which the strap is gripped, and the part (*g*) having the strap attached thereto.
- 35 The foregoing specification signed at Berlin, Germany, this 15th day of May, 1931.

JOHANN PLESCH.
